[57] **CLAIM**

The ornamental design for a light fixture, as shown and described.

DESCRIPTION

FIG. 1 is a top perspective view of a light fixture showing our new design;

FIG. 2 is a front elevational view thereof, the rear elevational view thereof being a mirror image of FIG. 2;

FIG. 3 is a top elevational view thereof;

FIG. 4 is a right side elevational view thereof, the left side elevational view being a mirror image of FIG. 4;

FIG. 5 is a bottom elevational view thereof;

FIG. 6 is a right side elevational view of a second embodiment showing our new design which is identical to the embodiment of FIGS. 1-5 but with the addition of two continuous circumferential grooves as shown, the left side elevational view being a mirror image of FIG. 6;

FIG. 7 is a front elevational view of the embodiment of FIG. 6, the rear elevational view thereof being a mirror image of FIG. 7 and the top and bottom elevational views thereof being identical to FIGS. 3 and 5, respectively;

FIG. 8 is a right side elevational view of a third embodiment showing our new design, which is identical to the embodiment of FIGS. 1-5, but with a flat lens rather than a convex lens, the left side elevational view being a mirror image of FIG. 8; and,

FIG. 9 is a front elevational view of the embodiment of FIG. 8, the rear elevational view thereof being a mirror image of FIG. 9 and the top and bottom elevational views thereof being identical to FIGS. 3 and 5, respectively.

The broken line representations of fittings in FIGS. 1, 2 and 4-9 are shown for environment only and form no part of the present invention.
